Specification of Letters Patent

Patented Jan. 1, 1918.

Application filed April 17, 1916. Serial No. 21,985.

15 *to all whom it may concern:*
Be it known that I, RAYMOND L. PIJUMTEK,
a citizen of the United States of America,
residing in Wilmington, county of New
Castle, and State of Delaware, have in-
5 vented certain new and useful Improve-
ments in Straw Sewing Machines, of which
the following is a true and exact descrip-
tion, reference being had to the accompany-
10 ing drawings, which form a part thereof.

My present invention comprises improvements in sewing machines devised with the special object of producing what is known as a straw sewing machine capable of operation at the high speeds required by modern factory use, with a minimum of noise and vibration, and with provisions whereby the necessary adjustments to compensate for wear may be readily and accurately made. More specifically my invention comprises improvements in the means employed for giving the needle and presser bars of the type of sewing machine referred to, their accustomed movements.

25 The various features of novelty which characterize my invention are pointed out with particularity in the claims annexed to and forming a part of this specification. For a better understanding of the invention,
30 however, and the advantages possessed by it, reference should be had to the accompanying drawings and descriptive matter in which I have illustrated and described a preferred embodiment of my invention.

Fig. 2 is a side elevation of a straw sewing

Fig. 3 is a partial section on the line 3—3 machine embodying my invention;

40 of Fig. 24 and in which all the parts to Fig. 4 are of section on the line A-B of

Fig. 4 is a section on the line 4-4 of Fig. 3; it shows the barrier of the novel cell structure.

Fig. 5 is a section on the line 5-5 of Fig. 2, showing all the main features.

45 Fig. 6 is a perspective view of a split bushing employed in the needle lever mounting; and

Fig. 7 is an elevation illustrating a detail. The straw sewing machine shown in the

50 The straw sewing machine shown in the drawings comprises a G-shaped frame A, in the lower portion of which is journaled the main shaft B of the machine. Through an eccentric B' carried by the main shaft B, and a connecting rod C the usual oscillating

1915. Serial No. 21,985. The frame A is provided with a lever D and a connecting rod C. The lever D is pivoted to the frame A, and the connecting rod C is connected to the lever D and to its driving eccentric B by ball and socket joints as is usual in this type of machines. With this arrangement there is a tendency for the connecting rod to wobble and rattle. To prevent this I provide helical springs D² which act at all times between the upper head of the connecting rod C and the adjacent portion of the lever D. As shown, there are two of these springs seated in sockets D¹ and horizontally disposed one on each side of, and in substantially the same horizontal plane with, the center of the ball and socket connection between the connecting rod C and the lever D. These springs exert a balanced thrust on the upper end of the connecting rod. The adjustable mounting for the needle lever stud F and the provisions just described for obviating the tendency of the connecting rod C to wobble and rattle are not claimed here.

in, but are claimed in my application, Serial No. 78,110, filed February 14, 1916 as a division of this application.

In the head A' of the frame A are mounted a vertical reciprocating needle bar H and presser bar I. The needle bar H is mounted in upper and lower bushings h and h' which are clamped in split ear portions A² and A³ of the frame. The needle bar is given its up and down movement by means of a yoke H', adjustably clamped to the needle bar H between the bushings h and h', and links D³ connecting the yoke H' to the free end of the lever D. The presser bar I, which carries the usual presser foot i at its lower end, is held against rotative movement by means of a crosshead or yoke member J which is adjustably clamped to the bar H above the frame head A'. J' represents the split clamping ears by which this adjustable connection of the member A to the upper end of the needle bar I is effected. The member J comprises an arm J² formed with a passage way near its free end receiving the upper end of the bushing h which is extended above the upper end of the frame head A' for this purpose. To permit of the adjustment of the bearing between the bushing h and the arm J², the latter is split the bifurcations being connected by a clamping screw J⁴. To insure the exact adjustment desired a shim J⁵ is interposed between the bifurcations of the arm J² at one side of the bushing h. The use of a shim in a split bearing of this kind permits of a very easily made and accurate adjustment. As the parts wear and the bifurcations of the arm J² need to be drawn closer together the shim is removed and filed or ground away a trifle and then replaced. Should a shim be made too thin in effecting any adjustment of this sort, it is a simple and inexpensive matter to replace the thin shim with a thicker one. By proceeding in this manner the bearing may be adjusted to the exact size required in which case it is neither too loose on the one hand, and on the other does not grip the bushing h. Moreover, nothing is left to chance as would be the case were it attempted to secure an adjustment without the shim. In such case the resiliency of the bifurcations of the arm J² are balanced so to speak, against the tension of the clamping screw J⁴ and vibration tends to work the screw loose. With the shim the screw may be set up so tightly that it can not work loose in normal operation. The adjustable bearing construction just described is not claimed herein, but is claimed in my application, Serial No. 78,111, filed February 14, 1916, as a division of this case.

With the arrangement described the presser bar is very accurately held against rotation not only because of the tightness of the bearing of the yoke member J on the

shaft formed by the upper end of the bushing h, but also because of the very considerable distance between the presser bar and bushing h. Owing to the adjustable connection between the presser bar and yoke J formed by the clamping ears J', the presser bar may be raised and lowered with reference to the yoke J and the mechanism engaging the latter as hereinafter explained, in a very simple manner.

As shown, the member J is provided with an extension J⁵ at the rear side of the presser bar. This extension is engaged on the upper side by the bar spring K, which tends to hold the presser foot down against the work, and has its tension adjusted by the adjusting screw K' carried by the frame. The under side of the extension J⁵ is adapted to be engaged by the lever L pivotally connected at L¹ to the frame and intended to have its long arm connected to a treadle by depressing which, the presser foot can be elevated. A spring L² normally holds the lever L out of engagement with the arm J⁵. The usual presser foot lifting cam M, journaled on the stud A⁴ carried by the frame A, also engages the under side of the member J⁵ to lift the presser foot when the cam M is normally rotated on its bearing stud for this purpose.

In certain operations performed with sewing machines of this type, for instance, in forming the usual "button" at the center of the crown of a straw hat, it is necessary to lift the presser foot off from the work to permit the adjustment of the latter once for each stitch taken. My present invention comprises a novel form of "tipping" mechanism for automatically accomplishing this purpose. As shown, this mechanism comprises a two armed lever member N, which is mounted on the horizontal stud A⁵ secured to the frame of the machine and is axially movable thereon from the position shown in full lines to the position shown in dotted lines in Fig. 3. A spring arm Q passing through an aperture formed in the lower arm N² (see Fig. 7) of the member N, tends to hold the latter in whichever of its two positions it is moved accordingly as the hump O' of the spring is at one side or the other of the arm N². The arm N' of the member N extends under the arm J² of the member J, and when the lever N is turned in a clockwise direction, the crosshead J is engaged by the arm N', and the presser bar and presser foot are thereby lifted. The oscillating movement of the member N is brought about, when the member is adjusted into the full line position of Fig. 3, through the engagement of the arm N², by a reciprocating member P. As shown, the arm N² is actually engaged by a screw P³ adjustably secured in the lug P² projecting from one side of the member P, which has an extension P' loosely received and sliding in a correspond-

ing passage way formed through the head A'. At its opposite end the member P is connected by means of the stud D⁵ to the needle lever D above the bearing stud F for the latter. The reciprocation of the member P, when the lever N is in the position shown in full lines in Fig. 3, causes the presser foot to be lifted off the work once during each stitch forming operation and during the portion thereof in which the needle penetrates the work and serves as a fulcrum in adjusting the latter. The free end of the extension P' engages the thread tension spring Q' to release the tension of the latter on the thread in the tension box Q on each movement of the needle into its lowermost position.

The use of a member, arranged and operating substantially as does the member P, 20 as a tension releasing actuator is not novel, but it is novel with me, I believe, to utilize such a member to operate a "tipping mechanism" for lifting the presser foot off from the work once during each stitch forming 25 operation. The operation of the "tipping mechanism" in this manner possesses certain very important advantages over the heretofore used arrangements in which the "tipping mechanism" is directly operated by the 30 front end of the needle lever D. For one thing the velocity of the stud D⁵ and consequently of the member P, is very much lower than the velocity of the front end of the needle lever. Furthermore, the connection 35 of the "tipping mechanism" to the needle lever adjacent the pivotal support of the lever, instead of near the front end of the latter, permits a reduction in weight of the lever especially at its front end and thus 40 permits of a substantial reduction in the inertia of the lever. The reduction in lever inertia, and the reduction of the velocity of operation of the "tipping mechanism" both contribute to an avoidance of vibration, 45 noise and wear.

Cooperating with the needle carried by the needle bar H and located beneath the work bed or table of the machine may be any suitable stitch forming mechanism, but inasmuch as the features of novelty claimed herein do not pertain to the character of this stitch forming mechanism or to the character of the work guiding mechanism and work feeding mechanism collectively 50 designated by the symbols S and R respectively, no more specific reference to these parts of the sewing machine disclosed need be made.

While in accordance with the provisions 55 of the statutes I have illustrated and described the best form of my invention now known to me, it will be apparent to those skilled in the art that changes may be made in the form of apparatus disclosed without departing from the spirit of my invention

and that in some cases some features of my invention may be used without a corresponding use of other features.

Having now described my invention what I claim as new and desire to secure by Letters Patent, is:

1. In a sewing machine the combination with the frame and oscillating needle lever pivotally connected thereto, of a presser foot, a member having one end pivotally connected to the said lever adjacent the pivotal axis of the latter and its other end in guided relation with said frame whereby said member is reciprocated in the direction of its length by the oscillation of said lever, and a tipping mechanism mounted on said frame and adapted to be actuated by said member to lift said presser foot off the work once during each stitch forming operation.

2. In a sewing machine, the combination with the frame and the oscillating needle lever pivotally connected thereto, of a presser bar mounted in said frame, a yoke secured to the upper end thereof, a member having one end pivotally connected to said lever adjacent the pivotal axis of the latter and having its other end in guided relation with the said frame whereby said member is reciprocated in the direction of its length by the oscillation of said lever, a tipping lever mounted on said frame and adjustable relative to said member into and out of a position in which it is engaged and oscillated by said member as the latter is reciprocated, and provided with an arm adapted to engage said yoke and lift said presser bar when oscillated.

3. In a sewing machine, the combination with the frame and the oscillating needle lever pivotally connected thereto, of a presser bar mounted in said frame, a tension device mounted on said frame, a tension releasing device comprising a member having one end pivotally connected to the said lever adjacent and above the pivotal axis of the latter and its other end in guided relation with said frame whereby said member is reciprocated in the direction of its length by the oscillation of said lever, a tipping lever mounted on said frame and axially adjustable in a direction transverse to the line of movement of said member into and out of the position in which said lever is engaged and oscillated by said member as the latter reciprocates and a yoke secured to the upper end of said presser bar and engaged by the lever and thereby oscillated as said tipping lever is oscillated.

4. In a sewing machine, the combination with the frame and the needle bar mounted therein, of a bushing forming a bearing for the needle bar and mounted in said frame and projecting above the upper end of the latter, a presser bar mounted in said frame

parallel to the needle bar, a yoke adjustably secured to the upper end of the presser bar and formed with a bearing slidingly receiving the projecting upper end of the bushing and mechanism adapted to engage said yoke and lift said presser bar.

5. In a sewing machine, the combination with the frame and the needle bar mounted therein, of a bushing forming a bearing for 10 the needle bar and mounted in said frame and projecting above the upper end of the latter, a presser bar mounted in said frame parallel to the needle bar, a yoke adjustably secured to the upper end of the presser bar 15 and formed with a bearing slidingly receiving the projecting upper end of the bushing, a needle lever, a tipping mechanism for engaging said yoke and lifting said presser bar comprising a lever pivotally mounted in 20 said frame and having an arm adapted to engage said yoke, and an operating connection between said lever and the needle lever.

6. In a sewing machine, the combination

with the frame and the needle bar mounted therein, of a bushing forming a bearing 25 sleeve for the latter mounted in said frame and projecting above the upper end of the latter, a presser bar mounted in said frame parallel to the needle bar, and a yoke secured to the upper end of the presser bar and 30 formed with a bearing slidingly receiving the guiding shaft formed by the projecting upper end of said bushing.

7. In a sewing machine, the combination with the frame and the needle bar mounted 35 therein, of a bushing forming a bearing sleeve for the needle bar and mounted in said frame and projecting above the upper end of the latter, a presser bar mounted in said frame parallel to the needle bar, and a 40 yoke secured to the upper end of the presser bar and formed with an adjustable split bearing slidingly receiving the projecting upper end of the bushing.

RAYMOND L. PLUMLEY.

Copies of this patent may be obtained for five cents each, by addressing the "Commissioner of Patents, Washington, D. C."
